UNITED STATES PATENT OFFICE.

WILLIAM F. SPRENGNETH, OF ST. LOUIS, MISSOURI.

SPARK-PLUG.

1,310,847.

Specification of Letters Patent. Patented July 22, 1919.

Application filed April 14, 1918. Serial No. 289,791.

To all whom it may concern:

Be it known that I, WILLIAM F. SPRENGNETH, a citizen of the United States, residing at St. Louis, State of Missouri, have 5 invented certain new and useful Improvements in Spark-Plugs, of which the following is a full, clear, and exact description, reference being had to the accompanying drawings, forming a part hereof.

10 My invention has relation to improvements in spark-plugs for explosive engines and is directed more particularly to that kind of plug which is readily removable for inspection; and it consists in the novel 15 construction more fully set forth in the specification and pointed out in the claims.

In the drawings, Figure 1 is a section of the upper part of an engine cylinder with the spark-plug applied thereto; Fig. 2 is a 20 top plan of the spark-plug; Fig. 3 is a side elevation of the plug; Fig. 4 is a front elevation of the same; and Fig. 5 is a side elevation of the spark-plug proper detached from the holder.

25 The present invention is directed to a spark-plug provided with a holder from which it may be easily and quickly detached, at the same time permitting of a simple and durable construction that can be manufactured at small cost; further advantages will 30 be better apparent from a detailed description of the invention which is as follows:

Referring to the drawings, E represents an engine cylinder into the head of which 35 a threaded socket 1 provided with a hexagonal portion 2, is screwed. The spark plug proper consists of a cylindrical metallic casing 3, provided with an exterior flange a, and interior shoulder b, said casing receiving a porcelain insulator 4 having an annular enlarged portion or flange d, said flange resting on the shoulder b of the casing 3 and being held in place by a screw 5 threaded into the upper part of the 40 casing. The plug is also provided with an electrode 6, inside the insulator 4, terminating in a terminal 7 from which a wire w leads, and a short electrode 8 secured into the lower end of the casing 3. These latter 45 features are well known in the art.

50 The spark-plug proper is inserted into the socket 1, the casing 3 passing through the opening O of the socket 1, a gasket 9 being interposed between the flange a of the casing 55 and the hexagonal portion 2 of the socket. A yoke 10 is pivotally secured to opposite

faces f, f, of the hexagonal portion 2, by a pair of links 11, 11, said yoke also being pivoted to the links 11, 11, by means of pins 12, 12, thus permitting the yoke 10 to straddle the upper part of the casing 3 and rest on the flange a of the casing. The yoke 10 is provided with a centrally disposed lug 13 on its upper edge e, through which a set screw 14 passes. The manner of securing 60 the spark-plug into the socket and removing the same may be described as follows:

After the spark-plug has been inserted into the socket O, the yoke is brought up over the flange a upon which it rests, and 70 the set screw 14 is screwed down tightly against said flange. The pressure of the set screw clamps the spark-plug firmly into the socket between the yoke 10 and the hexagonal portion 2 of the socket, as shown full 75 in Fig. 3. In order to release the spark-plug the set-screw is unscrewed and the yoke allowed to drop down to the position shown dotted in Fig. 3, whereupon the spark-plug can be lifted out of the socket.

80 It is obvious that with a sufficient amount of slack in the wire w, the spark-plug can be removed from the socket and laid on the engine, where its operation may be readily observed with little or no trouble. If found 85 to be operating satisfactorily it can be just as easily slipped back into place.

Having described my invention what I claim is:

1. A spark-plug provided with a metallic 90 casing, said casing having an annular flange, a socket adapted to receive said spark-plug, a pair of links pivotally secured to said socket, a yoke pivotally secured to said links, and a set-screw passing through the yoke 95 and adapted to bear upon the annular flange of the metallic casing.

2. A spark-plug provided with a metallic casing said casing having an annular flange, an exteriorly screw-threaded socket adapted 100 to receive said spark-plug, a pair of links pivotally secured to said socket on opposite sides thereof, a yoke pivotally secured to said links adapted to straddle the casing and rest on the flange thereof, and a set-screw passing through the yoke and bearing on the flange of the casing.

3. A spark-plug provided with a metallic casing having an annular flange, a socket adapted to receive said spark-plug, a pair 110 of links pivotally secured to said socket, a yoke pivotally secured to said links, the yoke

- being provided with a lug on its upper edge, and a set-screw passing through said lug and adapted to bear upon the flange of the casing.
- 5 4. A spark-plug comprising a metallic casing provided with an internal shoulder and an external flange, an insulating member having an annular enlarged portion, said insulator being inserted into the casing, the
- 10 enlarged portion thereof resting on the shoulder of the casing, a screw-plug adapted to hold said insulator in place, an electrode passing through the insulator, a socket
- adapted to receive the metallic casing, a gasket interposed between the flange of the 15 casing and the socket, a pair of links pivotally secured to said socket, a yoke pivotally secured to said links, and a set-screw passing through the yoke and adapted to bear upon the annular flange of the casing. 20
- In testimony whereof I affix my signature, in presence of two witnesses.

WILLIAM F. SPRENGNETHER.
